UNITED STATES PATENT OFFICE.

OSCAR RODRIGUEZ, OF CHICAGO, ILLINOIS.

VALVE.

Application filed July 3, 1920. Serial No. 393,886.

To all whom it may concern:

Be it known that I, OSCAR RODRIGUEZ, a citizen of the United States of America, residing at Chicago, in the county of Cook 5 and State of Illinois, have invented new and useful Improvements in Valves, of which the following is a specification.

This invention relates to valves for use on brake lines, steam lines and the like, the 10 principal object of the invention being to provide means for locking the valve in its open and closed positions so that there is no danger of the valve being turned from one position to the other by the jarring of 15 the train or the like.

Another object of the invention is to provide means whereby the air may leak through the valve from the closed part of the line when the valve is in closed position. 20 This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying drawings wherein like characters denote 30 like or corresponding parts throughout the several views, and in which:—

Figure 1 is a side view showing my improved valve as connecting two parts of a pipe line together.

Figure 2 is a plan view of the valve.

Figure 3 is a longitudinal sectional view with parts in elevation.

Figure 4 is a plan view of the upper part 40 of the valve body, with the other parts removed therefrom.

Figure 5 is a perspective view of a column.

Figure 6 is a fragmentary view of the upper part of the handle.

In these views 1 indicates the valve, 2 45 the pipe leading from the steam or air supply and 3 the pipe for leading the steam or air to the point of use, these pipes being suitably connected with the valve casing, as shown. The valve member 4 is provided 50 with the usual port 5 for permitting the steam or air to pass through the valve casing when the valve member is turned to place the port in alignment with the end portions of the casing but when the valve member is given a quarter turn the port 55 will be placed crosswise and the passage

through the casing will be closed. The bottom part of the valve chamber in the casing is closed by a screw plug 6 and a spring 7 is located in said chamber and has one 60 end pressing against the plug and the other end against the valve member so as to force said valve member upwardly into tight engagement with the walls of the chamber. A shallow recess 8 is formed in the valve 65 member on one side thereof and so located that when the valve member is in position closing the passage through the casing this recess will register with the forward part of the passage so that the steam or air in 70 the pipe 3 may pass into said recess and through the groove 9 into the lower part of the chamber, which is occupied by the spring 7, and pass through the vent 10 formed in the plug. Thus the air or steam 75 in the closed portion of the pipe line will escape when the valve is closed.

The stem 11 of the valve member projects through the top of the casing and a disc 12 has a square hole in the center thereof for receiving the stem and the disc is secured to said stem by the pin 13 passed through the hole 25 as shown in Figure 5. This disc has its lower face engaging the flat top of the casing and this part of the 80 casing has a recess 14 therein which is one-fourth of a circle and the disc carries a projection 15 which fits in said groove. This recess and projection limit the rotary movement of the disc and valve member to a 85 quarter circle. A cross shaped projection 16 is formed on the upper face of the disc. A handle 17 is provided for actuating the valve and this handle is provided with circular head 18 of cup shape to fit over the 90 disc 12 and this head is provided with a cross shaped opening 19 for receiving the cross shaped projection 12 on the disc. Ears 20 are formed on the head and an ear 21 is formed on the disc, this ear 21 fitting between the ears 20 and a pin 22 passing through the ears hinges the handle to the disc. The handle is bent downwardly to conform to the shape of the casing and the inclination of pipe 3. The handle carries 100 a projection 23 on its under face for engaging the locking projections 24 on the upper part of the casing, these projections holding the handle and the valve member against further movement when they are in 105 engagement with each other.

It will thus be seen that when the valve

is to be moved the handle must be swung upwardly on the pin 22 so as to free its projection from the locking projections on the casing. Then the handle is turned to 5 rotate the valve to open and closed position. The cross shaped projection 16 engaging the opening 19 will permit vertical movement of the handle in relation to the disc while transmitting the rotary movement of the handle to said disc and valve member.

It is thought from the foregoing description that the advantages and novel features of my invention will be readily apparent.

15 I desire it to be understood that I may make changes in the construction and in the combination and arrangement of the several parts, provided that such changes fall within the scope of the appended claims.

20 What I claim is:—

1. A valve of the class described comprising a casing, a valve member therein for controlling the passage through the casing, said member having a recess and a groove 25 therein for permitting the steam in the forward part of the pipe line to leak into the lower part of the casing below the valve member and a plug closing said lower part of the casing and having a vent therein.

30 2. A valve of the class described comprising a casing having a vertically extending chamber therein, a valve member in said chamber, a screw plug closing the bottom of the chamber and having a vent therein, a

spring located between the valve member 35 and said plug, said valve member having a recess in one side and a groove for permitting the steam of the forward part of the casing to leak into the lower part of the chamber and through the vent when the valve 40 member is closed.

3. A valve of the class described comprising a casing, a valve member therein, a disc connected with the valve member, a handle member having a head enclosing the 45 disc, means for hinging the handle member to said disc, a cross shaped projection on the upper part of the disc and the head having a cross shaped opening for receiving said projection and interlocking projections 50 on the head and casing for holding the valve in its open and closed positions.

4. A valve of the class described comprising a casing, a valve member therein, a disc connected with the projecting end of the 55 valve member, a projection on the disc and the casing having a groove therein for receiving said projection, said projection and groove acting to limit the turning movement of the valve to a quarter turn, a 60 handle member having a head enclosing the disc, means for hinging the head to said disc and interlocking projections on the head and casing for holding the valve member in open and closed positions. 65

In testimony whereof I affix my signature.

OSCAR RODRIGUEZ.
